RELEASABLE FIN ASSEMBLY

Charles L. Barker, Dundalk, and Raymond G. Gavial, Baltimore County, Md., assignors to The Glenn L. Martin Company, Middle River, Md., a corporation of Maryland

Application May 7, 1951, Serial No. 225,042

6 Claims. (Cl. 244—87)

1

This invention relates generally to aerodynamic stabilizing devices and more particularly to a releasable fin assembly adapted to function as a vehicle providing a stabilized flight path for testing reaction type motors such as rocket boosters.

In conducting certain experimental tests on disposable rocket boosters adapted for use as auxiliary power units on aircraft, it is necessary to simulate the actual flight conditions wherein the booster is released from the aircraft to fall earthward when its thrust producing propellant is expended. This testing is accomplished by propelling the booster into the air by means of its own thrust and then allowing it to fall earthward when the propellant is expended. However, since such reaction motors are not by themselves aerodynamically stable bodies so as to maintain a predictable flight path, stabilizing means must be provided which will be released from the booster before it begins its descent. The releasable fin assembly shown in the drawing and described in this specification represents the stabilizing means permitting such tests to be conducted in a manner simulating actual operation in service on an aircraft.

An object of this invention is to provide a releasable fin assembly adapted to be carried by a reaction motor for maintaining stabilized flight for a predetermined period of time and then to automatically free itself from the motor.

Another object of this invention is to provide a releasable fin assembly having means for positively causing its release irrespective of external aerodynamic forces.

Still another object of this invention is to provide a releasable fin assembly which is light in weight and economical to manufacture.

Further and other objects will become apparent from the accompanying description and drawings which form a part of this disclosure and in which like numerals refer to like parts.

In the drawing:

Figure 1 is a fragmentary side view of the releasable fin assembly carried by a reaction type motor.

Figure 2 is a sectional side view of the fin assembly nose.

Figure 3 is a sectional view taken on line 3—3 of Figure 1.

For purposes of illustration, releasable fin assembly 1 is described as a test vehicle for a disposable rocket type booster 2. Ring member 3 of the fin assembly is adapted to seat against the rearward exhaust end 4 of rocket housing 55

2

5. The gases produced by the propellant 6 within rocket 2 pass through nozzle 7 and into the airstream through the aperture 8 in ring member 3. Four equally spaced brackets 9 are suitably secured to ring member 3 such as by welding. Arms 10 are swingably connected to the brackets by means of pins 11. Arms 10 extend generally normal to ring 3 and closely adjacent housing 5 of booster 2 to form a cage. Fin assembly nose 12 is adapted to seat against the forward end 13 of booster 2 and connect with the free ends 10' of arms 10 which extend beyond the forward end of the booster. A swept back fin 28 is rigidly secured to each arm 10 adjacent ring member 3 to provide the aerodynamic stability required for maintaining a predictable flight path. Arms 10 throughout a major portion of their length are T-shaped in cross section as shown in Figures 1 and 3. This shape not only increases the rigidity of the assembly, but also adds to the stabilizing effect produced by the fins.

Fin assembly nose 12, generally ogival in shape, includes a tip member 14 and a base member 15. The small end 16 of base member 15 is provided with an axial bore 17 forming a piston chamber as shown in Figure 2. Tip member 14 carries a piston member 18 adapted to be slidably received in bore 17 for limited axial movement. For assembling and disassembling nose 12, piston member 18 is made to threadedly engage tip member 14. Four dowels 19 disposed radially from piston member 18 and extending generally parallel thereto, form a part of tip member 14 for securing the free ends 10' of arms 10 in fixed position relative to nose 12 and thereby effect a rigid assembly capable of withstanding external loads and accelerations. This securing of arms 10 is accomplished by having dowels 19 extend through apertures 20 formed in arms 10, as shown in Figure 3, and into holes 21 drilled in base member 15. A plurality of generally radial bores 22, one for each arm, are provided in base member 15. Bores 22 communicate with bore 17 intermediate of the extreme axial positions of piston 18. Auxiliary pistons 23 are carried in each bore 22 for movement therein so as to contact arms 10 and cause the assembly to be released from booster 2 as hereinafter described.

Internally of base member 15, a delay type igniter 24 is secured to hollow supporting structure 25 in communication with bore 17. Supporting structure 25 forms a part of base member 15. An explosive charge 26 such as gunpowder is inter-

posed between piston 18 and igniter 24 within hollow supporting structure 25 which is detonated by means of igniter 24. An actuating cable or pull wire 27 extending into base member 15 connects with igniter 24. By pulling cable 27, the igniter is triggered for exploding the charge at the end of the predetermined delay period.

To assemble the booster and fin assembly, arms 10 are disconnected from nose 12 and swung outwardly about pivot 11 by moving tip member 14 away from base member 15 to disengage dowels 19 from apertures 20. Then the booster is placed between arms 10 so that its exhaust end rests on ring 3. Next, nose 12 is seated on the forward end 13 of booster 2 in generally co-axial relationship and arms 10 are swung into position so that apertures 20 mate with holes 21. The fin assembly is then locked in position caging booster 2 by moving tip member 14 towards base member 15 to allow dowels 19 to pass through aperture 20 and into holes 21.

Nose 12 being ogival in shape presents a low drag fairing which permits the booster to attain a greater range and fins 28 provide the necessary stability for maintaining a predictable flight path.

The booster with its attached fin assembly may be launched as a rocket in conventional fashion by means of suitable launching apparatus, such as an inclined trackway at the launching site. Cable 27 is adapted to be automatically pulled to initiate the operation of the time delay igniter just before the booster assembly leaves the launching apparatus. After the predetermined time period has elapsed during flight, igniter 24 detonates the explosive charge 26. The expanding gases produced thereby act against piston 18 to cause tip member 14 to move away from base member 15 so that dowels 19 will completely release arms 10, as indicated in dotted lines in Figure 2. When piston 18 has moved sufficiently so that generally radial bores 22 are in communication with the expanding gases produced by the explosive charge 26, auxiliary pistons 23 are caused to move outwardly and into contact with the underside of arms 10 and thereby force the arms to swing outwardly about their pivots 11, irrespective of any drag forces which may be present tending to prevent such swinging movement. When arms 10 are freed from nose 12, the fin assembly falls free of the rocket.

Though the fin assembly is described herein in connection with experimental testing of disposable boosters, it is obviously equally well adapted to other uses.

It is to be understood that certain changes, alterations, modifications and substitutions can be made without departing from the spirit and scope of the appended claims.

We claim as our invention:

1. A releasable fin assembly adapted to provide a stabilized flight path for reaction type motors comprising a ring adapted to seat against the rearward exhaust end of the motor, a plurality of stabilizing arms swingably connecting at one end with said ring and extending generally normal thereto and beyond the forward end of the motor, a streamlined nose having a tip member and a base member, said base member being adapted to seat against the forward end of the motor in generally coaxial relationship therewith, an axial bore formed in said base member and having an opening adjacent said tip member,

5 a piston secured to said tip member and adapted to be slidably received in said bore for axial movement relative thereto whereby said tip member is supported for movement toward and away from said base member, said nose being adapted to secure the free ends of said arms extending beyond the forward end of the motor when said tip member is moved toward said base member and to release said arms when said tip member is moved away from said base member, a plurality of generally radial bores formed in said base member and communicating with said axial bore, said radial bores having openings adjacent the underside of said arms, auxiliary pistons carried in said radial bores adapted for movement into contact with said arms whereby force is applied thereon tending to cause swinging movement away from said nose, and pressure means carried by said base member and communicating with said bore for actuating said first mentioned piston and said auxiliary pistons so as to move said tip member away from said base member and apply force to said arms for positively releasing said fin assembly.

2. A releasable fin assembly adapted to provide a stabilized flight path for a reaction type motor comprising, a ring adapted to seat against the exhaust end of the motor, a plurality of arms having their rear ends pivotally connecting with said ring and normally extending forwardly beyond the opposite end of the motor to form a cage surrounding the motor, fins carried by said arms providing aerodynamic stability, a nose, generally ogival in shape, adapted to seat against the opposite end of the motor in generally co-axial relationship therewith, said nose including securing means releasably engaging the forward ends of said arms whereby said fin assembly is held fixed relative to the motor, means carried by said nose for actuating said securing means for releasing said arms, and means carried by said nose and adapted to engage said arms to forcibly urge said arms outwardly upon release of said arms by said securing means.

3. A releasable fin assembly adapted to provide a stabilized flight path for a reaction type motor comprising a plurality of arms extending axially of the motor to form a cage surrounding the motor and carrying fins thereon to provide aerodynamic stability, a ring adapted to seat against the exhaust end of the motor, said ring being pivotally connected to one end of each of said arms, a nose having a base member and a tip member, said base member being adapted to seat against the opposite end of the motor and having a bore formed therein adjacent said tip member, a piston secured to said tip member and slidably received within said bore for axial movement relative to said base member whereby said tip member is supported for movement toward and away from said base member, said tip and base members being adapted to secure the free ends of said arms therebetween when said tip member is moved towards said base member and to free said arms when said tip member is moved away from said base member, and pressure means carried by said nose and coacting with said piston for actuating said piston so as to move said tip member whereby to release said fin assembly.

4. A releasable fin assembly adapted to provide a stabilized flight path for a reaction type motor comprising, a ring adapted to seat against the exhaust end of the motor, a plurality of stabilizing arms swingably connecting at one end with said ring and extending generally normal ther-

to and beyond the forward end of the motor so as to form a cage therefor, a nose, generally ogival in shape having a tip member and a base member, said base member being adapted to seat against the forward end of the motor in generally coaxial relationship therewith, said base member having a bore formed therein co-axial with said tip member, a piston, rigid with said tip member, adapted to be slidably received within said bore for axial movement relative to said base member whereby said tip member is supported for movement toward and away from said base member, the free ends of said arms projecting between said tip and base members and adapted to be secured therebetween when said tip member is moved toward said base member and released therefrom when said tip member is moved away from said base member, pressure means co-acting with said piston so as to move said tip member away from said base member, and pressure responsive means carried by said base and communicating with said pressure means when said tip member is moved away from said base member for causing said arms to swing outwardly about their swingable connection with said ring whereby to release said fin assembly.

5. A releasable fin assembly adapted to provide a stabilized flight path for an aerodynamically unstable body comprising a plurality of stabilizing arms extending longitudinally of and closely adjacent the body, a ring adapted to seat against the rear end of the body and pivotally connect with one end of said arms, a streamlined nose having a base member and a tip member adapted to secure the free ends of said arms, said base member being adapted to seat against the opposite end of the body whereby to confine the body within said arms, nose and ring, tip member supporting means secured to said tip mem-

ber and slidably carried by said base member for movement relative thereto, said tip member being movable toward said base member for securing said arms therebetween and being movable away from said base member for releasing said arms, and means carried by said nose for moving said tip member away from said base member for releasing said fin assembly.

6. A releasable fin assembly adapted to provide a stabilized flight path for an aerodynamically unstable body comprising, a ring adapted to seat against one end of the body, a plurality of arms pivotally connecting with said ring and extending generally normal thereto and beyond the opposite end of the body, stabilizing fins carried by said arms, a nose, generally ogival in shape, adapted to seat against the body between said arms extending therebeyond, said nose including means for releasably securing said arms thereto whereby said fin assembly is held fixed relative to the body, means carried by said nose for actuating said securing means for releasing said arms, and means carried by said nose and engaging said arms for moving said arms outwardly and free of said nose upon their release by said securing means.
